UNITED STATES PATENT OFFICE.

THOMAS J. BUTLER, OF HARRISON, NEW JERSEY.

GUN.

Application filed May 29, 1924, Serial No. 716,620. Renewed May 28, 1926.

This invention relates, generally, to improvements in guns; and, the present invention has reference, more particularly, to a novel construction of apparatus, in the form of a gun, from which a projectile or projectiles may be fired, with accelerating speed, without the employment or use of an explosive firing charge or charges, so as to produce a noiseless, as well as a smokeless device or apparatus for firing projectiles.

The principal object of the present invention is to provide an apparatus, in the form of a gun, and of a simple and efficient construction, for firing a projectile or projectiles from a bore, without the employment of an explosive firing medium, as powder or the like; and, furthermore, to provide a simple and effectively operating mechanical means, for propelling a projectile or projectiles with accelerating speed through the bore of the gun and from the firing nozzle thereof.

The invention has for its further object to provide a noiseless and smokeless apparatus or gun for firing a projectile or projectiles, with great speed or velocity, the general arrangement and operation of the mechanism being such, that all vibrating effects are reduced to a minimum, to provide a gyroscopic or stabilizing effect or action of the gun, and that a perfect aim may be had; and, furthermore, to provide a gun of the general character hereinafter more fully described, which is capable of a laterally swinging motion, in a horizontal plane, and the projectile-firing bore of which may also be angularly adjustable, in a vertical plane, so as to deliver the projectile at a higher or lower angle, as may be necessary.

Another object of the present invention is to provide a projectile-firing apparatus or gun, in which the projectile-propelling means may be actuated by manually operated means, or by electric or other power-operated means.

The invention has for its further object to provide a breech-loading gun of the character specified, with a view of providing a gyroscopic or stabilized effect under all conditions, a reliable feed for feeding projectiles into the gun, and certain other features of advantage referred to in detail hereinafter.

With the various objects of the present invention in view, the said invention consists, primarily, in the novel gun hereinafter more

fully set forth; and, the said invention consists, furthermore, in the novel arrangements and combinations of the various devices and parts, as well as in the details of the construction of the said parts, all of which will be more fully described in the following specification, and then finally embodied in the clauses of the claims, which are appended to and which form an essential part of the said specification.

The invention is clearly illustrated in the accompanying drawings, in which:—

Figure 1 is a plan view, and Figure 2 a side elevation of one form of gun made according to and embodying the principles of the present invention.

Figure 3 is a horizontal sectional representation of the gun, with certain portions of the gun omitted from said figure, said section being taken on line 3—3 in said Figure 2, looking in the direction of the arrow α ; Figure 4 is a similar sectional representation of the gun, said section being represented as being taken on line 4—4 in said Figure 2, looking in the direction of the arrow γ ; and Figure 5 is a longitudinal central vertical section of the parts represented in said Figures 3 and 4, said section being taken on line 5—5 in said Figure 3, looking in the direction of the arrow ν .

Figure 6 is a fragmentary section through the loading chamber and feed-hopper of the apparatus; Figure 7 is a semi-diagrammatic perspective of the loading-actuating means of the gun; and Figure 8 is a cross section on line 8—8 in said Figure 4.

Figure 9 is a side elevation of a small arm-gun adapted to be carried by an individual when not in use, and to be employed in the manner as is usual with the ordinary repeating rifle or similar gun, said view showing another embodiment of the principles of the present invention; and Figure 10 is a transverse vertical section of the same, said section being taken on line 10—10 in said Figure 9, and said view being made on an enlarged scale.

Figure 11 is a detail transverse sectional representation, on an enlarged scale, of the bore or barrel of the gun, showing one of a pair of oppositely located projectile-feeding discs in connection therewith; and Figure 12 is a detail horizontal sectional representation, said section being taken on line 12—12 in said Figure 10.

Figure 13 is a side elevation of the loading end of the gun, as shown in Figure 1, equipped with a belt-feed instead of a hopper; and Figure 14 is a similar view of the 5 reverse or ejecting side of said loading end of the gun and of the said projectile-provider or cartridge-belt.

Figures 15, 16, 17 and 18, are horizontal 10 sectional views, showing the breech construction, as used in said Figures 13 and 14, said views illustrating in succession the various steps of feeding the belt through the apparatus, and detaching and forcing the projectiles into the bore or barrel of the gun 15 and between the first set of the projectile-feeding discs; Figure 19 is a transverse vertical section through the same; and Figure 20 is an enlarged elevation of the belt-exit portion of the gun.

20 Similar characters of reference are employed in all of said figures, to indicate corresponding parts.

Referring now to the several figures of the drawings, and more especially to Figures 3, 25 4 and 5, the reference-character 1 indicates a suitably shaped chambered casing, provided at one end with an opening, as 2, and being provided at its other end with a butt 3, the said butt being formed with a projectile 30 receiving chamber 4. In communication with the chamber 4 is a magazine of any suitable design and construction, herein shown as comprising angularly disposed container-elements 5 in which the projectiles 35 6 are loaded, and are adapted to be successively fed by means of a spring-actuated follower-plate 7, in each element 5, into the said receiving chamber 4, substantially as indicated in Figure 6 of the drawings. In 40 communication with the said chamber 4 and disposed in an opening 8 in the wall 9 of the casing 1, is the receiving end of a tubular element 10, providing what may be termed the barrel or bore of the gun. This barrel 45 or bore 10 extends longitudinally through the casing 1, with its opposite end-portion projecting from the opening 2, substantially as shown. In its lower wall 11, at a suitable location, the said casing 1 is preferably 50 made with a chambered off-set, as 12, and extending laterally on opposite sides of the wall-portion 13 are flange-elements 14 for the oscillatory or rotary support of the casing 1 upon the supporting head or block 15, 55 of a supporting locating tripod of any usual construction and which may be provided with a seat, as 17, properly placed for seating the operator back of the gun. Usually 60 the means of supporting connection between the flange-elements 14 and the supporting head or block 15 is the conventional journal-mechanism, as indicated at 18 in Figure 2 of the drawings, so that the gun, while being oscillatorily disposed in a horizontal 65 plane, may also be moved in a vertical plane.

In addition, the casing 1 may be provided with the usual shoulder rest or guard 19 and an arrangement of sights 20 and 21. A protector-shield 22' may also be employed with the gun, as indicated in Figures 1 and 2 in 70 the drawings. Suitably disposed within the casing 1, and located outside of and on opposite sides of the said tubular element or barrel 10 is a projectile-feeding mechanism for feeding or passing the projectiles with 75 accelerated or increased speed through the barrel or bore, and for properly discharging the projectile from the firing end of the said barrel or bore.

As shown, this mechanism comprises a series of spindles, in this instance ten of such spindles being employed, and which are respectively indicated by the reference-characters 22, 23, 24, 25, 26, 27, 28, 29, 30 and 31, the several spindles having their respective end-portions both slidably and rotatably journaled in elongated holes, as 32, disposed in a pair of partitions or plates 33 and 34, with which the casing 1 is provided. Coiled springs 35 are located between and are suitably attached at their respective ends with the respective spindles 22 and 23, 24 and 25, 26 and 27, 28 and 29, and 30 and 31, the tendency of the said springs being to draw the spindles of each pair of spindles toward each other, and for the purposes to be hereinafter more fully set forth. Mounted upon the upper portion of the spindle 22, as more particularly shown in Figure 5 of the drawings, is a large sprocket-wheel or pulley 36 and upon a lower portion of said spindle 24 is a small sprocket-wheel or pulley 37, while similarly disposed upon the upper portion of the spindle 23 is a large sprocket-wheel or pulley 38, and upon a lower portion of said spindle 25 is a small sprocket-wheel or pulley 39. Upon the lower portion of the spindle 24 is a large sprocket-wheel or pulley 40 and upon the lower portion of the spindle 26 is a small sprocket-wheel or pulley 41. Similarly 45 mounted upon the spindle 25, upon the lower portion thereof, is a large sprocket-wheel or pulley 42, and upon the lower portion of the spindle 27 is a small sprocket-wheel or pulley 43. Upon the upper portion of the spindle 26 is a large sprocket-wheel or pulley 44, and also upon the upper portion of the spindle 27 is a large sprocket-wheel or pulley 46. Mounted upon the upper portion of the spindle 28 is a small sprocket-wheel or pulley 45, and upon the lower portion of the spindle 28 is a large sprocket-wheel or pulley 48. Similarly, the spindle 29 has mounted upon its upper portion, a small sprocket-wheel or pulley 47, and upon the lower portion of the spindle 29 is a large sprocket-wheel or pulley 50.

Mounted upon the lower portion of the spindle 30 is a small sprocket-wheel or pulley 49, and in a like manner, the lower por-

tion of the spindle 31 is also provided with a small sprocket-wheel or pulley 51. Link-chains or belts 52 are passed over the respective sprocket-wheels or pulleys 36 and 37, 5 40 and 41, 44 and 45, 48 and 49; and in like manner, link-chains or belts 53 are passed over the respective sprocket-wheels or pulleys 38 and 39, 42 and 43, 46 and 47, 64 and 51, as will be clearly evident from an inspection of Figures 3 and 5 of the drawings.

As shown in said Figures 3 and 5, and in Figures 8 and 11, the previously mentioned barrel or bore 10 is provided in its opposite sides, suitably spaced so as to be in alignment with the respective spindles 22 and 23, 15 24 and 25, 26 and 27, 28 and 29, and 30 and 31, with oppositely located openings, as 55 and 56, into which project under normal initial conditions, portions of the peripheries 20 of certain projectile feeding or propelling discs or wheels, as 57, 58, 59, 60, 61, 62, 63, 64, 65 and 66, the said discs being respectively mounted upon the spindles 22, 23, 24, 25, 26, 27, 28, 29, 30 and 31. As indicated 25 more particularly in said Figure 11, the peripheral portion of each propelling disc is made concave in cross-section, this concaved peripheral portion being preferably lined with a soft gripping material 67, such as 30 felt, or the like. Rotary motion of the several spindles, and the various elements carried by said spindles may be produced in several different ways, either by hand by the operator, or by means of an electric motor, 35 or other power-driven mechanism.

As shown more particularly in Figure 4 of the drawings, the spindles 26 and 27, or for that matter any other pair of spindles, are respectively provided with gears 68 and 40 69, which are always in mesh with each other. Attached to the lower portion of the spindle 27 is a bevel-gear 70 with which is in mesh a bevel-gear 71, mounted upon a shaft 72 rotatably disposed in a bearing-portion 45 73 in the wall of the main casing 1. Mounted upon the outer end-portion of the said shaft 72 is another bevel-gear 74 in mesh with a bevel-gear 75 mounted upon a rearwardly extending shaft 76, rotatably disposed in bearing-positions 77 with which the 50 said wall of the casing 1 is provided. The said shaft 76 is also provided with a bevel-gear 78 which is in mesh with a bevel-gear 79 mounted upon a crank-shaft 80, also rotatably disposed in a bearing-portion 81 in the wall of the casing 1, and adapted to be 55 actuated by a crank 82.

Thus, when the gunner or operator turns this crank, the motion is conveyed to the 60 spindle 27 and by means of the gearing 68 and 69 to the spindle 26, the motive power connected with the spindle 27, to be presently described being disconnected with said spindle, as will be evident, turning in opposite directions. Owing to the arrangement

of the gear-mechanism and the connecting link-chains, the rotation of the respective spindles 24 and 25, and 22 and 23, with relation to the spindles 26 and 27 is reduced, while the rotation of the respective spindles 70 28 and 29, and 30 and 31, with relation to said spindles 26 and 27 is increased, in any ratio that may be desired, so that the cartridge or projectile fed into the receiving end 75 of the tubular element or barrel 10 at first moves slowly between the first two discs 61 and 62, but moves with increasing or accelerated motion between the discs 59 and 60, 57 and 59, 63 and 64, and 65 and 66, to be 80 discharged from the firing end of the tubular element 10 with greatly increased speed, as will be evident.

In lieu of the above described manually operated means for actuating the projectile-engaging and firing means, the spindle 27 85 may have detachably connected therewith by means of suitably constructed attaching socket 83, or other suitable means, a flexible shaft 84 which is suitably connected with and is suitably operated from an electric motor, as 85, adapted to be placed in circuit with a source of electricity by means of the electric cables 86 and 87. The circuit through the wires within the cable 86 normally is interrupted or broken, but is readily established by the operator, by means of the contact-making devices 88 and 89, suitably connected with a grasping butt, as 90, of the conventional shape, and as will be 95 clearly understood from an inspection of Figures 2 and 5 of the drawings.

In order to conform as nearly as possible with the usual ordnance methods, and to obviate the need of special instruction of the operator, I have provided the usual pistol-grip or butt 91; provided with a spring-actuated contact-member for the purpose herein described, so that whenever the gunner tightens his hold on the pistol-grip, the motor will 105 be set in motion, and upon releasing his grip the motor will stop. This method is of great advantage because it will be obvious that should the gunner be shot or fail to keep his hold on the pistol-grip, the gun will cease to shoot. In order to make the gun 110 further conform to common practice, I provide the breech with the usual trigger 92, positioned in a recess 93 in the under face of the breech-block, the actual finger-grip 94 being pivotally mounted on one end of an L-shaped bar 95 adapted to move longitudinally in a bore 96 to one side of and communicating with the recess 93, the other end of said bar 95 being connected to a crank-lever 97, pivoted intermediate its ends 115 in the slot 98 in the breech, the said lever having a slot therein for the reception of a pin 99 attached to one face of a plunger 7. One arm of the L-shaped bar 95 is reduced, as at 101, and is provided with a coil-spring 120

102 and a collar 103, said collar 103 being fixed on said reduced portion 101, and acting as an abutment for said spring 102. In operation, when the finger-piece or grip 94 is pulled backward, it pulls the bar 95 with it, the bar thereby imparting a forward swinging motion to the slotted arm 98^a of the lever 97; and thus through the pin 99, a forward motion to the plunger 7, thereby pushing a projectile into position in the gun barrel. During this operation, the spring 102 is compressed, and the spring 102 being attached at one end to the face of the bore 96; and, abutting, as has been stated against 15 the collar 103 on the reduced portion 101 of the L-bar 95 upon releasing the trigger 94, the spring 102 will return the respective parts to their initial positions, permitting the operation being repeated to insert each 20 shell.

Should it be desired, however, to insert the projectiles automatically the trigger or finger-piece 94 is lifted into the position shown in dotted lines in Figure 3 and Figure 4 in which position it is in line with a plunger 104 mounted at one side of the breech, and adapted to be reciprocated backward and forward by means of a cam 105 attached to one of the propelling disc-shafts, said cam 25 having engagement with a wear-shoe 106 on one end of the plunger 104, the plunger being urged toward the cam by any suitable means, such as a spring 107, fastened at one end to the plunger, and at its opposite end 30 to the bearing thereof. From this it will be seen, that the action of the plunger back and forth will impart the same action to the finger-piece, as was produced by the gunner's finger, it being understood that there is 35 a slot 108 provided in the breech to permit the finger-piece to move back and forth in its raised position. It will be noted from the above description that the gun can be quickly changed from being manually operated, to being automatically operated; and, from being manually loaded to being automatically loaded, these items being of utmost importance in case of failure of any 40 of the above methods in active use. Furthermore all of these method-changes can be accomplished without the operator or gunner changing his position from behind the gun and losing either sight of his target or the protection of the shield.

With the style of infantry gun or small arm illustrated in Figure 9 of the drawings, as a modification, the general arrangement of the mechanism for propelling a projectile with increasing velocity through and from 45 the barrel of the gun, this mechanism is substantially the same as that herein-above described, except that with the actuating gears 68 and 69 have arranged between them and in mesh with the teeth 109 and 110 thereof a 50 rack 111, see Figures 10 and 12, the said rack

being connected by means of a connecting member 112 with a grasping element or member 113 movably disposed upon a guiding frame 114 carried by the casing 1 of the gun shown in said Figure 9 of the drawings. Additional gears or pinions, as 115 and 116 are also in this case mounted upon the respective spindles 22 and 23 with which spring-controlled pawls or dogs 117 and 118 are in engagement in a manner, so that during 55 the forward movement of the member 112 and of the rack 111, the pawls or dogs 117 and 118 the said pawls or dogs will actively engage the gears 115 and 116, these gears being keyed to their respective shafts 60 and in turn imparting a rotary movement to the propelling discs. It will be seen that by this construction the propelling discs will be rotated in one direction only, as the pawls will ride freely over the gears 115 and 116 65 on the return stroke. It is obvious that by placing the pawls in an opposite direction from that as shown, the pull-back stroke of the member 112 can be made to become the active stroke instead of the forward or 70 pushing operation. It will be noted that the method just stated (known as pumping) is in common use on many of the well-known guns, and will require little or no instruction in order to learn its use. In the present 75 form of gun, however, and shown in Figure 9, I find it of advantage to place the hopper above the breech and let the projectiles feed in by gravity, the hopper being, as in my preferred form, V-shaped, there 80 being enough space between the two legs of the V in order to have ample vision.

In referring to Figure 14 it will be noted, that in place of the V-shaped hopper as shown in my preferred form of gun, shown 85 in said Figure 1, and also in the modification illustrated in Figure 9, I have equipped the gun with the usual cartridge belt 119, carried in the usual box 120, the said belt being provided with pockets 121 for the reception 90 of the projectiles 122, the belt entering the gun-breech through an opening 123, and going through a similar opening 124 located on the opposite side therefrom, as will be seen clearly by reference to Figures 19 95 and 20.

In order to insert the projectiles in the breech-end of the gun-barrel, and at the same time hold the belt from being misplaced, due to the operation of pushing the 100 shell out of its belt-pocket, and in order to give to the belt an intermittent movement in one direction, I have provided the breech-chamber in this modification with spring-actuated clamping members 125 and 126, 105 which are positioned one above and one below the entrance-opening 123 of the breech, in such a manner as to be capable of vertical movement, the clamping members being normally urged toward each other by springs 110

128 and 129, positioned one above and one below each clamping member respectively. The breech is further provided with a bore 130 in which is positioned a plunger 131, 5 having a shoulder 132 at one end, a reduced portion 133, and a head 134 on the end of said reduced portion, the purpose of which will be later more fully described. The plunger 131 is normally urged toward the 10 end 135 of the bore 130 by a coil-spring 136 which bears against the shoulder 132 of the plunger and a shoulder 137 of the bore 130. Positioned upon the reduced portion 133 of the plunger 131 is a prong-shaped 15 member 138 which, when the plunger is in normal or retracted position, is clamped between the head 134 and the rear wall 139 of the cavity 140.

In order to impart forward motion to the 20 plunger 131, I have provided the operating member 141, which is identical with the same member 96 in my prepared form, with a roller 142, the supporting shaft of which protrudes through a slot 143 in the bore 130 25 and a slot 144 is the operating member or arm 141, the said roller bearing against the rear face of the plunger.

In operation of my device here stated, the belt is threaded through the breech, until 20 one of the shells is in line with the gun-barrel, or until the shell rests between the concave portions 145 of the clamping members, the end of the belt protruding slightly on one side, as at 146. It will be seen, that the 30 clamping members will securely hold the belt in this position until they are separated, whereby the member or arm 141 is actuated in a forward direction, as shown in Figure 16, thus pushing the plunger forward, compressing the spring 136, and putting the head 134 in contact with the rear end of the shell. This does not, however, have any action upon the member 138, which remains as before at the rear end of the cavity 140. Upon 40 further movement of the arm 141, as shown in Figure 17, it will be seen that the head 134 has pushed the shell out of its containing pocket and the shoulder 147 formed by the reduced portion 133 of the plunger 50 131, has pushed the member 138 forward until the cam-prongs 147 of said member engage in the recesses 148 formed in the clamping members 125 and 126, and thereby spread these members apart and release the 55 belt.

Upon the movement of the arm 141 backward, the plunger is retracted, but the member 138 still continues to hold the clamping members separated until the head 134 again 60 engages it and moves it again into the position shown in Figure 15. In order to feed the belt through the breech and at the same time produce an intermittent motion I have provided the breech with shafts 149 and 150, 65 positioned across the exit-aperture and have

provided these shafts with pronged wheels 151 and 152 respectively for the purpose of gripping the belt as it passes between them. In order to rotate the members 151 and 152 in opposite directions, and at the same time 70 impart an intermittent movement to them I provide the clamping members 125 and 126 with spring-actuated pawls 153 and 154, which are adapted to engage the ratchets 155 and 156 keyed to the shafts 149 and 150, 75 respectively, so that when the clamping device is expanding, the pawls will ride freely over their respective ratchets. Upon the next movement of the clamping device the pawls will engage and thus through the action of the wheels 151 and 152 will impart movement to the belt in the direction indicated by the arrow in Figure 19.

Having thus described my invention, it will be seen that I have produced a gun of 80 the types specified, which is simple, and highly effective, and at the same time easily assembled and does not require special instruction for use. It will be seen that my gun is also well adapted for use in air craft, 85 as it is free from the usual recoil; and, because of its gyroscopic quality, it is easily supported and kept in aim. It will be also noted that due to the fact that it is noiseless and smokeless it is well adapted for use 90 in trench warfare.

Briefly, and in summary, a rapid firing gun or apparatus made according to the principles of the present invention embodies the following essential features:—stabilized 100 or gyro-action; smokelessness; noiselessness; standard design of parts; no special instructions needed; can shoot the standard army projectiles; can shoot high explosive shells without losing any of their explosive charge 105 in order to fire; leaves no empty projectiles to close its former position; uses no gases; can shoot thin case-shells, with liquid container, or projectiles having a glass-con- 110 tainer, which cannot at present be fired because of the firing impact shattering the glass; projectiles passing in rapid succession into the bore of the gun, the projectiles almost abutting each other, because of the fact that there is no explosive charges carried 115 by the projectiles; and finally the gun needs no cooling.

Of course, I am fully aware that many changes may be made in the general arrangements and combinations of the various devices and parts of the apparatus, as well as in the details of the construction of the same, without departing from the scope of the present invention, as described in the foregoing specification, and as finally embodied in the clauses of the claims appended thereto. Hence, I do not limit my present invention to the exact arrangements and combinations of the various devices and parts as described in the said specification, 125 130

nor do I confine myself to the exact details of the construction of the said parts as illustrated in the accompanying drawings.

I claim:—

- 5 1. A gun of the character specified comprising a projectile-receiving barrel, means for feeding a projectile into said barrel, and mechanical and non-explosive mechanism located on opposite sides of said barrel for forcing the projectile through said barrel and finally expelling and firing the projectile from said barrel without any production of smoke.
- 10 2. A gun of the character specified comprising a projectile-receiving barrel, means for feeding a projectile into said barrel, and mechanical and non-explosive mechanism located on opposite sides of said barrel for forcing the projectile through said barrel and finally expelling and firing the projectile from said barrel without any production of noise due to explosive charges.
- 15 3. A gun of the character specified comprising a projectile-receiving barrel, means for feeding projectiles into said barrel, and rotary means located on opposite sides of the barrel for forcing the projectiles in succession through the barrel and expelling or firing the projectiles from said barrel.
- 20 4. A gun of the character specified comprising a projectile-receiving barrel, means for feeding projectiles into said barrel, and rotary means located on opposite sides of the barrel for forcing the projectiles in succession through the barrel and expelling or firing the projectiles from said barrel, combined with means for variously speeding the members of the said rotary means, and providing a stabilized effect or gyro-action of the gun.
- 25 5. A gun of the character specified comprising a projectile-receiving barrel, means for feeding projectiles into said barrel, and a speed-accelerating means located on opposite sides of the barrel for forcing the projectiles in succession and move them with accelerating speed through the barrel and expelling the projectiles at maximum speed from the barrel.
- 30 6. A gun of the character specified comprising a projectile-receiving barrel, means for feeding projectiles into said barrel, and rotary means located on opposite sides of the barrel for forcing the projectiles in succession through the barrel, combined with means for variously speeding the members of said rotary means, and move said projectiles with accelerating speed through the barrel and expelling the projectiles at maximum speed from the barrel.
- 35 7. A gun of the character specified comprising a projectile-receiving barrel, means for feeding projectiles into said barrel, said barrel being provided in its opposite sides with positioned openings, rotary discs lo-

cated on opposite sides of the barrel, said discs having their peripheral portions movable in the openings of the barrel, so as to grip the projectiles and to move the same through the barrel, and to expel or fire each projectile from the exit-end of the barrel.

8. A gun of the character specified comprising a projectile-receiving barrel, means for feeding projectiles into said barrel, said barrel being provided in its opposite sides with positioned openings, rotary discs located on opposite sides of the barrel, said discs having their peripheral portions movable in the openings of the barrel, so as to grip the projectiles and to move the same through the barrel, combined with means for variously accelerating the rotary speeds of the said discs and of the projectiles in their passage through the barrel and expelling the projectiles at maximum speed from the exit-end of the barrel.

9. A gun of the character specified comprising a projectile-receiving barrel, means for feeding projectiles into said barrel, said barrel being provided in its opposite sides with positioned openings, spindles located on opposite sides of the barrel and in alignment with the oppositely located openings, discs mounted upon said spindles, said discs having their peripheral portions movable in the openings of the barrel, so as to grip the projectiles and to move the same through the barrel, and to expel or fire each projectile from the exit-end of the barrel, gear-mechanism mounted upon said spindles for actuating said spindles and the discs, and means carried by a pair of said spindles for primarily actuating said pair of spindles.

10. A gun of the character specified comprising a projectile-receiving barrel, means for feeding projectiles into said barrel, said barrel being provided on its opposite sides with positioned openings, spindles located on opposite sides of the barrel and in alignment with the oppositely located openings, discs mounted upon said spindles, said discs having their peripheral portions movable in the openings of the barrel, so as to grip the projectiles and to move the same through the barrel, and to expel or fire each projectile from the exit-end of the barrel, gear-mechanism mounted upon said spindles, geared in a manner for variously actuating said spindles and the discs, and means carried by a pair of said spindles for primarily actuating said pair of spindles.

11. A gun of the character specified comprising a projectile-receiving barrel, means for feeding projectiles into said barrel, said barrel being provided in its opposite sides with positioned openings, spindles located on opposite sides of the barrel and in alignment with the oppositely located openings, each pair of said oppositely located spindles being capable also of reciprocatory move-

- ments, coil-springs connected with and located between each pair of spindles, discs mounted upon said spindles, said discs having their peripheral portions movable in the 5 openings of the barrel, so as to grip the projectiles and to move the same through the barrel, and to expel or fire each projectile from the exit-end of the barrel, gear-mechanism mounted upon said spindles for actuating 10 said spindles and the discs, and means carried by a pair of said spindles for primarily actuating said pair of spindles.
12. A gun of the character specified comprising a projectile-receiving barrel, means 15 for feeding projectiles into said barrel, said barrel being provided in its opposite sides with positioned openings, spindles located on opposite sides of the barrel and in alignment with the oppositely located openings, 20 each pair of said oppositely located spindles being capable also of reciprocatory movements, coil-springs connected with and located between each pair of spindles, discs mounted upon said spindles, said discs having 25 their peripheral portions movable in the openings of the barrel, so as to grip the projectiles and to move the same through the barrel, and to expel or fire each projectile from the exit-end of the barrel, gear-mechanism 30 mounted upon said spindles geared in a manner for variously actuating said spindles and the discs, and means carried by a pair of said spindles for primarily actuating said pair of spindles.
- 35 13. In a gun, in combination with the barrel and breech thereof, means for successively feeding projectiles into said breech, and mechanical and nonexplosive mechanism located on opposite sides of the barrel for forcing the projectiles through the barrel and expelling and firing the projectiles in rapid succession from said barrel without any production of smoke.
- 40 14. In a gun, in combination with the barrel and breech thereof, means for successively feeding projectiles into said breech, and mechanical and nonexplosive mechanism located on opposite sides of the barrel for forcing the projectiles through the barrel and expelling and firing the projectiles in rapid succession from said barrel without any production of noise due to explosive charges.
- 45 15. In a gun, in combination with the barrel and breech thereof, means for successively feeding projectiles into said breech, and rotary means located on opposite sides of the barrel for forcing the projectiles in succession through the barrel and expel the same 50 in rapid succession from said barrel.
- 55 16. In a gun, in combination with the barrel and breech thereof, means for successively feeding projectiles into said breech, and rotary means located on opposite sides of the barrel for forcing the projectiles in succession through the barrel and expel the same 60 in rapid succession from said barrel.
- 65 17. In a gun, in combination with the barrel and breech thereof, means for successively feeding projectiles into said breech, and a speed-accelerating means located on opposite sides of the barrel for forcing the projectiles in succession with accelerating speed through the barrel and expelling the projectiles at maximum speed from the barrel. 70
18. In a gun, in combination with the barrel and breech thereof, means for successively feeding projectiles into said breech, and rotary means located on opposite sides of the barrel for forcing the projectiles in succession through the barrel, combined with means for variously speeding the members of said rotary means, and move said projectiles with accelerating speed through the barrel and expelling the projectiles at maximum speed from the barrel. 75
19. In a gun, in combination with the barrel and breech thereof, said barrel being provided in its opposite sides with positioned openings, means for successively feeding projectiles into said breech, rotary discs located on opposite sides of the barrel, said discs having their peripheral portions movable in the openings of the barrel, so as to grip the projectiles and to move the same 80 through the barrel, and to expel or fire each projectile from the exit-end of the barrel. 85
20. In a gun, in combination with the barrel and breech thereof, said barrel being provided in its opposite sides with positioned openings, means for successively feeding projectiles into said breech, rotary discs located on opposite sides of the barrel, said discs having their peripheral portions movable in the openings of the barrel, so as to grip the projectiles and to move the same 90 through the barrel, combined with means for variously accelerating the rotary speeds of the said discs and of the projectiles in their passage through the barrel and expelling the projectiles at maximum speed from the exit-end of the barrel. 95
21. In a gun, in combination with the barrel and breech thereof, said barrel being provided in its opposite sides with positioned openings, means for successively feeding projectiles into said breech, spindles located on opposite sides of the barrel and in alignment with the oppositely located openings, discs mounted upon said spindles, said discs having their peripheral portions movable in 100 the openings of the barrel, so as to grip the projectiles and to move the same through the barrel, combined with means for variously accelerating the rotary speeds of the said discs and of the projectiles in their passage through the barrel and expelling the projectiles at maximum speed from the exit-end of the barrel. 105

ating said spindles and the discs, and means carried by a pair of said spindles for primarily actuating said pair of spindles.

22. In a gun, in combination with the barrel and breech thereof, said barrel being provided in its opposite sides with positioned openings, means for successively feeding projectiles into said breech, spindles located on opposite sides of the barrel and in alignment with the oppositely located openings, discs mounted upon said spindles, said discs having their peripheral portions movable in the openings of the barrel, so as to grip the projectiles and to move the same through the barrel, and to expel or fire each projectile from the exit-end of the barrel, gear-mechanism mounted upon said spindles geared in a manner for variously actuating said spindles and the discs, and means carried by a pair of said spindles for primarily actuating said pair of spindles.

23. In a gun, in combination with the barrel and breech thereof, said barrel being provided in its opposite sides with positioned openings, means for successively feeding projectiles into said breech, spindles located on opposite sides of the barrel and in alignment with the oppositely located openings, each pair of said oppositely located spindles being capable also of reciprocatory movements, coil-springs connected with and located between each pair of spindles, discs mounted upon said spindles, said discs having their peripheral portions movable in the openings of the barrel, so as to grip the projectiles and to move the same through the barrel, and to expel or fire each projectile from the exit-end of the barrel, gear-mechanism mounted upon said spindles for actuating said spindles and the discs, and means carried by a pair of said spindles for primarily actuating said pair of spindles, geared in a manner for variously actuating said spindles and the discs, and means carried by a pair of said spindles for primarily actuating said pair of spindles.

barrel, and to expel or fire each projectile from the exit-end of the barrel, gear-mechanism mounted upon said spindles for actuating said spindles and the discs, and means carried by a pair of said spindles for primarily actuating said pair of spindles.

24. In a gun, in combination with the barrel and breech thereof, said barrel being provided in its opposite sides with positioned openings, means for successively feeding projectiles into said breech, spindles located on opposite sides of the barrel and in alignment with the oppositely located openings, each pair of said oppositely located spindles being capable also of reciprocatory movements, coil-springs connected with and located between each pair of spindles, discs mounted upon said spindles, said discs having their peripheral portions movable in the openings of the barrel, so as to grip the projectiles and to move the same through the barrel, and to expel or fire each projectile from the exit-end of the barrel, gear-mechanism mounted upon said spindles for actuating said spindles and the discs, and means carried by a pair of said spindles for primarily actuating said pair of spindles, geared in a manner for variously actuating said spindles and the discs, and means carried by a pair of said spindles for primarily actuating said pair of spindles.

In testimony that I claim the invention set forth above I have hereunto set my hand this 28 day of May 1924.

THOMAS J. BUTLER.
